UNITED STATES PATENT OFFICE.

JACQUES R. FREEDMAN, OF NEW YORK, N. Y., ASSIGNOR TO FRANDOR MFG. CO., INC.,
OF NEW YORK, N. Y., A CORPORATION OF NEW YORK.

PACKAGING TEXTILE ARTICLES.

Application filed February 17, 1926. Serial No. 88,760.

This invention relates to certain novel and useful improvements in packaging textile articles.

The package of the present invention is intended to embrace a varied selection of sizes, designs and styles of either complete or ready-made garments, such as dresses, waists, shirts and other articles of wearing apparel, or such articles in a partially completed or a semi-made condition, or, the patterns of such articles, that is, individual fabric blanks marked with selected outlines or measurements and designed to be cut accordingly and to be sewed or made up by the purchaser, or, if desired, the package may comprise a desired combination or selection of various garment blanks together with garments either made or semi-made or both.

As is well-known, it is the present-day custom for manufacturers to pack, sell and ship such articles of wearing apparel as dresses, waists, shirts and the like, either one to a box, or a number of articles of the same size and design in a single box, and in some instances to put a number of articles of different designs but of the same size in the same box.

From the standpoints of transportation charges, storage and counter space, handling and display, these methods of packaging are expensive, uneconomical, cumbersome and inconvenient. When the goods reach the merchant the boxes are usually discarded and the contents placed or stacked on shelves, counters or in cases, and soon become soiled, rumpled, disarranged and unsightly, through handling and exposure. In addition, this method of packaging such goods limits the variety or selection of stock which the ordinary small merchant will purchase, because to carry a wide selection of designs or styles of different sizes requires a considerable financial investment, usually more than a small dealer can afford in the ordinary course of business. With this limitation of character of stock imposed upon the merchant it necessarily follows he cannot offer to his trade or customers the same wide selection or choice, as can the larger stores, and consequently is at a disadvantage in competition.

The above disadvantages are obviated by my invention, for it enables the manufac-

turer to provide the merchant or dealer, at a small investment, with a wide and varied selection or stock of ready-made or semi-made garments or garment patterns, in different styles, designs and sizes. I further provide a unitary, compact, sanitary and convenient package which may be easily and readily shipped, which will occupy but relatively little storage and counter space, and which, when displayed, will exhibit the character of the stock to advantage, while avoiding the necessity of handling the individual articles, thereby obviating the liability of soiling the latter. In other words, when the package containing the articles is on display, the character, size, style and design of the contents may be ascertained at a glance without requiring the handling of the individual pieces, thus avoiding the liability of disarranging and soiling the latter.

With the above recited objects and others of a similar nature in view my invention consists in the construction, combination and arrangement of parts, set forth in and falling within the scope of the appended claims.

In the accompanying drawings:

Fig. 1 is a perspective view of the package of textile articles embodying my invention.

Fig. 2 is a cross sectional view taken on the line 2—2 of Fig. 1.

Fig. 3 is a cross sectional view but showing the package container in closed position.

Referring now to the accompanying drawings in detail, the letter A indicates a box which may be of cardboard, fiber board, or other suitable material. In the present instance it is preferably oblong in form embodying a bottom 1, the end walls 2, back wall 3, and a front movable wall 4, hinged at its lower edge to the front longitudinal edge of the bottom 1, as shown at 5. This hinged or movable front wall 4 of the box or container is of less height or depth than the end wall 5, and when moved to vertical position to form the closed front of the box, its upper edge will act as a support for the removable tray T, as hereinafter described. Within the box or container A are arranged a suitable number of vertical partitions 6, dividing the box into a series of compartments 7. These compartments are also

shorter or of less height than the rear and end walls of the box A, and also preferably of slightly less depth than the swinging or movable front wall 4, so that when the front wall is in its vertical or closed position with the tray 6 resting on the upper edge thereof, the front portion of the tray bottom will be lifted slightly to be out of contact with the top edges of the partitions near the front of the latter. The purpose of this is to insure that the weight and pressure of the tray on and against the top edge of the movable wall 4 will hold the latter in its closed position at desired times, as shown 10 in Fig. 2. However, if it is desired that the box should be opened to exhibit all of the stock of goods, as shown in Fig. 1, the tray may be tilted upward or lifted for an instant, to permit the front wall 4 to drop 15 down thus exposing the goods, and the tray may then be allowed to settle back on the top edges of the partitions and be supported thereby, all as shown in Fig. 1.

As will be seen by reference to Fig. 1, and 25 as illustrating the manner of making up the package, I have shown resting in the tray three different garment patterns P, which may be of different styles, designs or sizes, and the tray also contains three completed 30 garments G of selected size, design and style.

The uncompleted garments or garments patterns P, as well as the completed garments G are arranged side by side in a row 35 in the tray, there being in such tray one garment of each style, design or size, so as to exhibit, without requiring handling, a full line of the stock contained in the package. The compartment 7 directly beneath or in line with the respective garment or 40 garment pattern contains a pile or stock of articles corresponding to such garment pattern or completed garments, as will be readily understood by reference to Fig. 1.

The box A is provided with a hinged 45 cover C connected with the box body by flexible brace straps 8 and having end flanges 9 and a front flange 10. These flanges are relatively deep, so that when the cover C is closed, as is shown in Fig. 3, the flanges 50 will depend to such a depth at the outside of the box body as to overlap the side edges and top front edge of the movable front wall 4 of the box, thereby retaining the same in closed position and against accidental 55 opening.

From the above description, taken in connection with the accompanying drawings, the construction and purpose of my invention will be readily apparent.

60 A selected stock of goods, made up as described in Fig. 1, and embodying both the stock or pile of garments in the compartments and the corresponding samples on the tray, are packed in the box and the front wall then moved to vertical or closed

position and retained by the weight of the tray resting on the open edge thereof. The top may then be closed down so that the flanges overlap the edges of the front wall of the box and the package may then be 70 packed for shipment to the merchant. On being placed on display at the store, the merchant may lift the cover C, thereby exposing the line of samples for the customer's selection, or, should the customer desire, any 75 one sample may be removed and examined in detail. At this time the front wall of the box is preferably kept closed by the weight of the tray, thereby protecting the stock of garments which are to be sold, 80 from dust, handling and soiling. When the customer has selected a garment or garment pattern, the merchant may momentarily lift 85 up or slightly tilt the front end of the tray, thereby permitting the front wall 4 to drop down, as shown in Fig. 1, then readily withdrawing the desired garment which has been selected according to sample. When the purchase has been completed the front end 90 of the tray is then again momentarily tilted upward, the wall 4 thrown vertically back into closed position, and the tray again dropped to allow it to rest on the front edge of the wall to hold the latter closed.

It will be noted by this arrangement that 95 not only do I provide a compact and convenient form of package enabling a relatively wide selection of stock of diverging character, style and design to be carried, but the stock to be sold will be protected 100 while on exhibition from exposure, the selection being made from corresponding samples on the tray.

While I have herein shown and described 105 one particular embodiment of my invention, I wish it to be understood that I do not limit myself to all the precise details set forth by way of illustration, as modifications and variation may be made without departing 110 from the spirit of the invention or exceeding the scope of the appended claims.

What I claim is:

1. A special package for the shipping and display of textile articles comprising a container subdivided by vertical partitions or 115 compartments, each containing a stock of garments or garment designs, said stocks differing from each other in characteristics and designs, a tray arranged above said compartments and containing a row of sample specimens corresponding in characteristics and design to the aligning stocks therebelow, said container having a front wall movable to expose the said compartments and stocks and a movable cover overlying said tray, said cover having a portion adapted to overlap and hold the front wall in closed position.

2. A package of textile articles comprising a container subdivided into compartments, said container having a movable wall of less 120

height than the remaining wall, and tray located within the container and adapted to rest upon the movable wall to hold the latter in closed position, said compartments having therein stocks of garments, ready-made or semi-made, said tray having arranged therein sample specimens corre-

sponding in characteristics and designs to the stocks in the compartments, and a movable cover for the container.

Signed at New York city, in the county of New York and State of New York, this 10th day of February A. D. 1926.

JACQUES R. FREEDMAN.
